UNITED STATES PATENT OFFICE.

THOMAS O. PATTIN, OF LOS ANGELES, CALIFORNIA.

HYDROCARBON-ENGINE.

1,157,728.

Specification of Letters Patent. Patented Oct. 26, 1915.

Application filed March 22, 1915. Serial No. 16,052.

To all whom it may concern:

Be it known that I, THOMAS O. PATTIN, a citizen of the United States, residing at Los Angeles, in the county of Los Angeles 5 and State of California, have invented a new and useful Hydrocarbon-Engine, of which the following is a specification.

My object is to reconstruct or make an attachment to a hydrocarbon engine for 10 automobiles and the like, so that when the engine is operated to run in the high gear, fresh air will be drawn by the suction of the engine through an injector mounted in the hot water pipe, running from the engine to 15 the top of the radiator and discharging in the direction of the flow of hot water, so as to cool the water, stimulate the flow of water, heat and moisten the air, said air being discharged or conducted from the radiator into the manifold of the engine above 20 the carbureter, so as to short circuit the carbureter to the desired extent, thereby reducing the suction through the carbureter, and so as to furnish a supply of hot, moist air to 25 be mixed with the explosive charge, thereby reducing the quantity of gasoline used and increasing the combustion, and lubricating the engine with water and provide means of adjusting the relative proportion of this hot, 30 moist air; and my invention consists of the novel features herein shown, described and claimed.

Figure 1 is a diagrammatic view showing the connection from the radiator to the 35 manifold and showing the operating and adjusting mechanism. Fig. 2 is a fragmentary inside elevation of the dash board, showing my adjusting mechanism in position for use. Fig. 3 is a fragmentary vertical section on the line 3—3 of Fig. 2 and looking in the direction indicated by the arrow, the engine and radiator being broken away. Fig. 4 is a fragmentary front elevation, as indicated by the arrow 4 in Fig. 3. Fig. 5 is an enlarged vertical sectional detail of the top of the radiator on a plane parallel 45 with the radiator shown in Fig. 1. Fig. 6 is an enlarged sectional detail of the throttle valve and taken on the line 6—6 of Fig. 3. Fig. 7 is a fragmentary vertical sectional detail on the line 7—7 of Fig. 5. Fig. 8 is an enlarged fragmentary sectional detail on the same plane as Fig. 3 taken on line 8—8 of Fig. 2. Fig. 9 is a fragmentary elevation 50 looking in the direction indicated by the arrow

9 in Fig. 8 and showing the attaching mechanism in position to operate the engine with the throttle valve normally wide open when the engine is running on a high gear and the parts being shown in the position occupied 60 when the valve is wide open. Fig. 10 is a view analogous to Fig. 9 with the adjusting dog set to open the valve half way when the engine is running in the high. Fig. 11 is a view analogous to Figs. 9 and 10 with 65 the adjusting dog set as in Fig. 9, that is, to throw the valve wide open, the parts being in the position occupied when the valve is closed, as when the engine is in neutral or running in the low gear.

The leading features of my invention comprise the combination with the engine 1 and the radiator 2 of the injector mechanism 3 mounted in the hot water pipe leading from the engine to the top of the radiator, the suction pipe 4 leading from the dome of the radiator, the throttle valve 5 connecting the suction pipe to the intake manifold 6 of the engine, the adjusting mechanism 7 for controlling the extent or the degree which the 75 throttle valve 5 will open and the operating mechanism 8 connecting the throttle valve 5 to the clutch lever or pedal 9, which controls the connection between the engine and the drive wheels.

The engine proper 1 may be of any suitable design used upon automobiles or the like, and the radiator 2 may be of any suitable type as ordinarily used in providing thermosiphon circulation for cooling the 80 engine.

The details of the injector 3 are as follows: The radiator 2 has a dome 10 provided with a filling neck 11 closed by a cap 12, and the inlet tube 13 extends downwardly and 95 backwardly from the dome and is connected to the top of the water jacket of the engine by a pipe 14. The strainer 15 is mounted in the dome so that water poured into the radiator through the neck 11 will pass through 100 the strainer. A pipe socket 16 is fixed through the center of the cap 12 and extends downwardly into the neck 11. A pipe 17 has a stop 18 upon its lower end and this pipe 17 is pushed tightly up through the 105 socket 16 until the stop 18 strikes the lower end of the socket. A pipe 19 leads from the stop 18 downwardly through the strainer 15 and laterally and downwardly into the tube 13 and a return bend 20 is formed upon 110

the lower end of this pipe, so that the discharge end 21 discharges in the direction of the flow of hot water from the engine to the radiator. The tubular casing 22 has a side opening through which the return bend 20 extends, so that the discharge end 21 is in the center of the casing, the casing being larger in diameter than the pipe 19.

The details of the suction pipe 4 are as follows: A metal pipe 23 extends from near the top of the neck 11 downwardly through the radiator to a position below the bottom of the radiator, and a flexible pipe or hose 24 is attached to the lower end of this pipe 23 by the connection 25 and leads to the connection 26.

The details of the throttle valve mechanism 5 are as follows: A nipple 27 is tapped through the wall of the intake manifold 6. A stop cock 28 is screwed upon the nipple 27. A nipple 29 is screwed into the stop cock. An elbow 30 is screwed upon the nipple 29 and a nipple 31 connects the elbow 30 and the connection 26. The carburetor 32 may be of any suitable type and it is connected to the intake manifold 6 below the passage through the throttle valve 5 to the manifold.

The details of the adjusting mechanism 7 are as follows: The stem 33 forms an extension of the valve 34 of the stop cock 28 and this stem extends through the bearing 35 in the dash-board 36. A stop 37 is rigidly mounted upon the rear face of the dash-board 36 near the bearing 35. The dial head 38 is rigidly and adjustably fixed upon the end of the stem 33 behind the dash-board 36. The end 39 of the stem 33 is screw seated in the head 38 and turned to the desired position and held rigidly by the jam nut 40. The dial plate 41 is rigid and concentric with the head 38 and has the graduations 42 upon its face. In the construction shown, the graduations 42 cover one fourth of a circle and read from zero by fractions, as $\frac{1}{4}$, $\frac{1}{2}$, $\frac{3}{4}$ to 1, and in adjusting the jam nut 40, the parts are assembled so that the zero graduation upon the dial plate 41 will be in line with the stop 37 when the throttle valve 5 is wide open, as in Figs. 1, 3 and 6. The adjustable stop finger 43 is carried by the head 44 fitting against the periphery of the dial plate 41, and an arm 45 extends from the head 44 to the bearing 46 and a screw 47 is inserted through the bearing 46 and screw seated in the center of the dial plate 41, so that the stop finger 43 will travel around the periphery of the dial plate 41. A set screw 48 is screw seated through the head 44 to engage the periphery of the dial plate 41 and hold the stop finger 43 in the desired adjusted position, and the stop finger 43 is in a concentric plane relative to the stem 33 to engage the stop 37 and limit the rotation of the stem 33 in that di-

rection. The coil spring 49 is mounted upon the stem 33, one end of the spring being connected to the stem and the other end of the spring being connected under tension to any suitable frame work, such as the manifold 6, and the tension of the spring 49 is exerted to rotate the stem 33 to carry the stop finger 43 against the stop 37. In adjusting the stop finger 43 to throw the throttle valve 5 wide open, the face of the stop finger 43 is moved to the graduation one upon the dial plate 41 and the set screw 48 is tightened. Then when the stop finger 43 is against the stop 37, as in Fig. 9, the throttle valve 5 is wide open. If the stop finger 43 is adjusted to the one-half graduation, as in Fig. 10, then when the stop finger 43 is against the stop 37, the throttle valve is one-half open, and in a similar manner the adjusting device may be set to open the throttle valve one quarter or three quarters, or to any desired fraction.

The details of the operating mechanism 8 connecting the throttle valve 5 to the clutch pedal 9 are as follows: The cam finger 51 extends from the stem 33 and when adjusting the mechanism 7 this finger is set to swing from the position shown in Fig. 9 to the position shown in Fig. 11 when the valve is to be operated from the closed to the wide open position, and to swing to the position shown in Fig. 10 when the valve is to be operated to open half way. In the position shown in Fig. 9, the finger 51 extends radially from the stem 33 upwardly at a left hand incline of forty-five degrees and in the position shown in Fig. 11, it extends downwardly at a right hand incline of forty-five degrees, and in the position shown in Fig. 10, it is straight up. The cam bar 52 is slidably mounted in bearings 53 upon the front face of the dash-board 36 and in a horizontal plane. The cam finger 54 projects and is connected to the cam bar 52 by a horizontal arm 55 operating in the bearing 56 to the vertical arm 57 and this cam finger 54 projects upwardly from the dash-board 36 parallel with the stem 33 and in position to engage the finger 51 when the bar 52 is reciprocated to the right so as to push the finger 51 against the tension of the spring 49, thereby by rotating the stem 33 and closing the throttle valve 5.

A vertical shaft 58 is mounted in bearings 59 upon the front face of the dash-board 36 and the crank arm 60 fixed upon the upper end of the shaft 58 is connected to the cam bar 52 by a link 61. A cam lever 62 is fixed upon the shaft 58 and has a cam slide 63 in which the cam arm 64 is slidably mounted and said cam arm 64 is connected by a rod 65 to the clutch pedal 9. A compression spring 66 is mounted upon the cam bar 52 between one of the bearings 53 and the stop 37, the tension of the spring being exerted

to throw the cam bar 52 to carry the cam finger 54 away from the finger 51 and allow the spring 49 to open the throttle valve.

In assembling the parts, the cam lever 62 is fixed upon the shaft 58 by the pin 68 in position so that when the clutch lever 9 is in position to operate the machine upon the high gear, the cam lever 62 will be against the face of the dash-board 36, as in Figs. 1 10 and 3, when the throttle valve 5 is wide open. Then, when the clutch lever 9 is operated out of the high gear position, the action of the cam arm 64 in the slide 63 will rotate the shaft 58 to throw the finger 51 against the tension of the spring 49 and close the 15 throttle valve 5.

In the drawings, I have shown the construction as applied to a regular Ford automobile and in this connection, it is understood that the clutch lever 9 throws the machine in the high gear when it moves toward the operator to the limit and that, when the operator pushes the clutch lever 20 forwardly to the neutral or to the low gear position, the throttle valve is closed and it is only open when the clutch lever is in the high gear position and that the extent to which it is then open is regulated by the adjusting mechanism 7. The principles of my 25 invention were applied to a 1914 Ford substantially as illustrated and it has been in operation for the past six months. When this throttle valve 5 is open, the suction of the engine through the throttle valve to the 30 dome of the radiator creates a vacuum in the dome and causes air to pass through the injector 3 and the action of the injector stimulates the flow of hot water from the top of the water jacket of the engine to the 35 radiator and this air, passing through the injector and passing through the hot water, causes the water to pile up in the top of the radiator, thus creating a light hydrostatic head for stimulating the flow of water down- 40 wardly through the radiator, thereby producing a rapid circulation without the use of any pump. This rapid circulation prevents the collection of sediment or rust in the water jacket passages and the speed of 45 the circulation is in direct proportion to the speed of the engine. The incoming air, being comparatively low in temperature, almost instantly absorbs the heat from the water, thereby raising the temperature of the 50 air and lowering the temperature of the water. The cool, fresh air is introduced into the circulating water at its hottest point and the passage of the air through this hot water produces a low temperature steam, and 55 this low temperature steam is drawn into the intake manifold 6 above the carbureter and mixes with the explosive charge, thereby lessening the suction through the carbureter and reducing the consumption of gasolene 60 and producing better combustion, and the 65

water vapor entering the cylinders tends to cool the cylinders and keep them from carbon deposit. In addition to this, I find that the muffler makes a great deal less noise, the motor runs smoother and with a decided reduction in vibration and labors much less when running at a very high speed.

The apparatus, being connected automatically to the clutch lever pedal in such a manner that it is in operation only when the 70 clutch is in the high gear position and off when in neutral or low gear, serves the double purpose of not spinning the motor when driving in the congested traffic district, but it does accelerate the motor the instant the 75 clutch lever pedal approaches the high gear position, thus enabling me to obtain a flexibility of control that did not exist before. By virtue of the peculiar shape of the slide 80 63 in the cam lever 62, the apparatus kicks 85 off and the throttle valve closes the instant the clutch lever leaves the high gear position.

It is obvious that the details of construction may be varied in many ways without 90 departing from the spirit of my invention, as set up in the following claims.

I claim:

1. In a hydro-carbon engine, the combination with engine cylinders, a water jacket 95 and a radiator connected at the top and bottom to the water jacket, of an injector mounted in the hot water pipe and discharging toward the radiator and means for drawing air through the injector and through the 100 intake manifold by the suction of the engine pistons.

2. In a hydro-carbon engine, engine cylinders, a water jacket around the engine cylinders, a radiator having a dome above the 105 level of the water jacket, a hot water pipe connection between the top of the water jacket and the top of the radiator, a cold water connection between the bottom of the radiator and the bottom of the water jacket, 110 an injector mounted in the hot water pipe and discharging in the direction of the radiator and having a fresh air inlet and a pipe connection between the dome of the radiator and the intake manifold.

3. The combination with a hydro-carbon engine and radiator, of an injector mounted in the hot water pipe and discharging toward the radiator, a suction pipe connecting the dome of the radiator to the intake manifold of the engine above the carbureter, and a throttle valve in the suction pipe.

4. In a hydro-carbon engine, an injector mounted in the hot water pipe and discharging toward the radiator, a suction pipe connecting the dome of the radiator to the intake manifold of the engine at a point between the carbureter and the engine, a throttle valve in the suction pipe, and means whereby the throttle valve is opened when 125 130

the engine is running to operate the automobile in the high speed.

5. In a hydro-carbon engine, an injector mounted in the hot water pipe and discharging toward the radiator, a suction pipe connecting the dome of the radiator to the intake manifold of the engine, a throttle valve in the suction pipe and a connection between the throttle valve and the mechanism for controlling the engine and automobile, whereby the throttle valve is open when the automobile is running in the high gear and closed at all other times.
6. In a hydro-carbon engine, an injector mounted in the hot water pipe and discharging toward the radiator, a suction pipe connecting the dome of the radiator to the intake manifold of the engine, a throttle valve in the suction pipe, a clutch pedal, a connection between the throttle valve and clutch pedal, whereby the throttle valve is closed

when the clutch pedal is out of the high speed position and opened when the clutch pedal is in the high speed position.

7. In a hydro-carbon engine, an injector 25 mounted in the hot water pipe and discharging toward the radiator, a suction pipe connecting the dome of the radiator to the intake manifold of the engine, a throttle valve in the suction pipe, a clutch pedal, a connection between the throttle valve and clutch pedal, whereby the throttle valve is closed when the clutch pedal is out of the high speed position and opened when the clutch pedal is in the high speed position, and 30 means for adjusting the extent to which the throttle valve will open.

THOMAS O. PATTIN.
